F. BALL.
PROCESS OF MANUFACTURING IRON COMPOUNDS.
APPLICATION FILED MAR. 16, 1920.
1,385,769. Patented July 26, 1921.

Inventor:

Frank Ball,

Attorneys

UNITED STATES PATENT OFFICE.

FRANK BALL, OF FARMINGDALE, LONG ISLAND, NEW YORK, ASSIGNOR TO WEST COAST KALSOMINE COMPANY, OF WEST BERKELEY, CALIFORNIA, A CORPORATION OF CALIFORNIA.

PROCESS OF MANUFACTURING IRON COMPOUNDS.

1,385,769.

Specification of Letters Patent. Patented July 26, 1921.

Application filed March 16, 1920. Serial No. 366,321.

To all whom it may concern:

Be it known that I, FRANK BALL, a citizen of the United States, residing at Farmingdale, Long Island, in the county of Nassau and State of New York, have invented certain new and useful Improvements in Processes of Manufacturing Iron Compounds, of which the following is a specification.

10 The present invention relates to the manufacture of iron compounds and more particularly to processes such as described in the Patent No. 1327061 granted Jan. 6, 1920 to R. S. Penniman, Jr. and N. M. Zoph, and 15 in the application Ser. No. 349,582 filed by R. S. Penniman, Jr. and N. M. Zoph, Jan. 5, 1920.

It is a general object of this invention to bring an oxidizing medium in direct and 20 positive contact with metallic iron and a more special object to bring a solution of ferrous sulfate in direct and positive contact with metallic iron in presence of an oxidizing agent.

25 Other more particular objects are—

1. To provide practical means for suspending metallic iron in the iron solution.

2. To provide means for circulating the iron solution past the metallic iron under 30 maximum oxidizing conditions.

3. To provide means for insuring the exposure of a maximum of surface of the iron to the action of the solution.

4. To provide means for effecting a constant and positive renewal of the fresh ferric sulfate solution in contact with the iron.

35 5. To provide means for promoting the reaction of the solution upon the iron and thereby increasing its speed and efficiency.

40 For a clearer understanding of the objects of the invention, the principles of operation and the result attained, reference is had to the accompanying drawing which is a sectional view of a simple arrangement of 45 the elements embodying the invention.

In the drawing 1 is an acid-proof tank of wood or other suitable material containing the working solution. A column of acid-proof material, such as a tile pipe 2, is set 50 in the tank upon acid-proof blocks, for instance timbers 3. This is merely one convenient way by which, similar to the placing of a tile pipe in a well, entrance of the liquid into the pipe is facilitated. It is understood

that any other means for permitting the unrestrained flow of the solution into the pipe is within the scope of the invention.

A conduit such as a pipe 4 preferably terminating in an upwardly directed outlet or nozzle 5 extends through the wall of the tank and through or between the timbers 3 and serves to discharge the oxidizing agent, which may preferably be air. In order to promote oxidation according to the processes defined in the patent and application above referred to the air may be heated before entrance into the apparatus. If desired, steam may be passed through the pipe 4 concurrently with the air. This feature is not shown in the drawing since it may be carried out in various ways and is not material to operation of the present invention.

In the top portion the pipe 2 is provided with a plurality of openings 6 preferably above the normal level of the solution in the tank, or, as an alternative, the pipe 2 might be cut off at the level of the openings 6.

The operation is as follows:

The metallic iron, preferably in the form of strips or thin sheets 7 defining a maximum of surface per unit volume, is placed in the pipe 2 so as to substantially fill it and yet permit the solution to freely pass therethrough.

When the air is admitted under pressure, it causes a violent agitation of the solution in the pipe and at the same time exerts a lifting action, causing a rise of the solution and overflow through the orifices 6. At the same time that portion of the solution discharged through the orifices 6 is replaced by a like quantity entering at the bottom. The rate of discharge and replacement per unit of time determines, of course, the rate of flow through the pipe and this rate may be controlled, within certain limits, by controlling the air pressure and the quantity of air admitted per unit of time.

The nozzle 5, it is understood, is so chosen or so set as to provide, at a certain air pressure, normally the most favorable rate of circulation.

It is understood that a plurality of air jets may be used instead of a single one. There is no limit to the adjustability or to the modification of the system in respect to the volume of air or the pressure applied.

While I have shown for the sake of sim-

2
plicity, a cylindrical tube or pipe, I also con-
template the use of other tubular bodies.

I claim:—

1. The process of producing iron com-
pounds, which consists in supporting pieces
of metallic iron in a vessel and passing a
stream of an oxidizing medium through the
vessel and through the body of iron therein.
2. The process of producing iron com-
pounds, which consists in supporting pieces
of metallic iron in an elongated vessel and
passing through the vessel and the body of
iron therein a stream of an oxidizing me-
dium comprising an aqueous fluid, adapted
15 to act as a vehicle for an oxidizing agent,
and the oxidizing agent.
3. The process of producing iron com-
pounds, which consists in supporting pieces
of metallic iron in a vessel and passing
20 through the vessel and the body of iron
therein a stream of an oxidizing medium
comprising an aqueous liquid, adapted to
act as a vehicle for air, and air.

4. The process of producing iron com-
pounds, which consists in supporting pieces 25
of metallic iron in a vessel and passing
through the vessel and the body of iron
therein a stream of an oxidizing medium
comprising an iron salt solution and an
oxidizing agent.

5. The process of producing iron com-
pounds, which consists in supporting pieces
of metallic iron in a vessel and circulating
through the vessel and the body of iron
therein a stream of an oxidizing medium 35
comprising an iron salt solution and air.

6. The process of producing iron com-
pounds, which consists in supporting a tu-
bular vessel containing pieces of iron in an
iron salt solution and forcing air together 40
with the solution through said vessel and
the body of iron contained therein.

In testimony whereof, I affix my signa-
ture.

FRANK BALL.
